STOCK CONDITION INDICATOR

Joseph Ross Conley, Birmingham, Mich.

Application November 13, 1950, Serial No. 195,179

2 Claims. (Cl. 116—135)

1

This invention relates to stock label holders for stock bins and other receptacles and, in particular, to devices for indicating the condition of the articles or materials in such receptacles.

One object of this invention is to provide a stock condition indicator for stock bins or other receptacles which is movably attached to the stock bin label holder and is slideable into and out of indicating position so as to indicate whether or not articles have been removed from the bins, so as to facilitate reordering articles to replenish the articles removed from the bins.

Another object is to provide a stock condition indicator which will remain with the bins at all times, and which will indicate at a glance the state of the contents of each of the bins.

In the drawings:

Figure 1 is a front elevation of several bins, showing the stock condition indicator in different positions of use;

Figure 2 is an enlarged view of a portion of a channel holder in Figure 1, containing the stock condition indicator in one position of use;

Figure 3 is an enlarged view of a portion of a channel holder in Figure 1 containing the stock condition indicator in another position of use; and

Figure 4 is a view of the stock condition indicator, shown in perspective.

Referring to the drawings in detail, Figure 4 shows a stock condition indicator, according to one form of the invention, generally indicated 10, and consisting of a short tab 11 and a long tab 12 secured together and to a base or support 13 by means of a fastener 14. The base 13 has opposite ends 15, and the tabs 11 and 12 constitute signal members and have nearer end portions 16 and 17 respectively through which the fastener 14 has been driven, and outer end portions 18 and 19 respectively, having rounded tips 20. The base 13 and the tabs 11 and 12 are preferably of flexible synthetic plastic. The short tab 11 is preferably red in color, and the long tab 12 preferably yellow, although any suitable color system may be substituted.

Figures 2 and 3 show the stock condition indicator 10 in use with a label or marker 21 in a channel 22 having bent retaining flanges 23 slidably holding the ends 15 of the base 13 in the grooves 24, formed by the bending of said flanges.

Figure 1 shows a number of stock condition indicators 10, similar to that shown in Figure 4, in different positions of use in connection with a conventional set or stack of storage bins, not a part of the invention. The channels 22 are se-

cured to shelves 25 by screws or fasteners 26 in conventional fashion. The shelf spaces are divided by vertical partitions 27 into bins or compartments 28.

In the use of the invention, the stock condition indicator 10 is placed within the channel 22 by inserting it in the end of said channel, with the ends 15 of the base 13 held in the grooves 24 by the retaining flanges 23. The indicator 10 may then be slid to the desired location, usually next to the label or marker 21 above or beneath the storage bin previously referred to. Alternatively, the indicator 10 may also be inserted directly from the front of the channel 22, the flexible nature of the plastic base 13, permitting it to be bent until both of the ends 15 are fitted in the grooves 24 before the indicator snaps into place beside the marker.

If the bin or compartment concerned is full, or has the normal amount of contents, such as a certain number of parts, the position of its indicator 10, according to one form of the invention, is with both of the tabs 11 and 12 extending behind the label 21 so that both of the outer end portions 18 and 19 respectively are concealed from view.

If, however, the stock clerk or other user removes a part from a compartment for any purpose, he registers the fact that the quantity of parts remaining therein is now below the standard amount by pulling the indicator 10 to the left away from the label 21 until the tip 20 of the short tab 11 is free of the label. He then pushes the indicator to the right, and raises the tab 11 slightly with the fingernail so as to permit the label or marker 21 to be wedged between the tab 11 and the tab 12 (Figure 2) with only the short red tab 11 visible, the long yellow tab 12 remaining concealed behind the marker.

At the time for re-ordering parts, the stock clerk checks his bin labels for those requiring replenishment of parts, as indicated by the red tabs 11 overlying certain of the bin labels 21. When a part or a number of parts has been ordered to replace that deficiency created by the previous removal of parts from the bin and marked by the red tab, as shown in Figure 2, this fact can also be registered by drawing the indicator 10 to the left so that both of the tabs 11 and 12 are clear of the label 21. The indicator 10 is then slid to the right, the operator meanwhile raising both the tabs so that their outer ends 18 and 19 extend over the face of the label 21 (Figure 3). In this position, both the red and the yellow tabs 55 are visible, and signify at a glance that the con-

tents of the bin designated are being brought up to the standard amount. When the ordered parts have arrived and have been placed in the bins requiring them, the tabs 11 and 12 of those bins are slid out from in front of their respective labels 21 and reinserted out of sight behind those labels.

A great advantage of this invention is its availability, requiring no pencil or other object which can be lost or misplaced, causing the user to postpone and later to forget the changing of the label. This indicator remains with the bin at all times, requiring only a quick, simple adjustment to indicate at a glance the state of the contents within the designated bin. The user may, however, carry extra indicators 10 in his pocket, if he so desires.

In a slight modification of the invention, the nearer end portion 16 of the short red tab 11 may be made of transparent material, painted or provided with a neutral color, and only the outer end portions 18 and 19 provided with signal colors, so that no red or yellow whatsoever can be seen when the outer end portions 18 and 19 of both tabs 11 and 12 are inserted behind the label 21 to show that a normal supply of articles is to be found in the bin. This facilitates a rapid inspection of a large stack of bins, a red color being visible only when the supply within a bin has been altered, and a yellow color only when replenishment parts have been reordered.

What I claim is:

1. A stock condition indicator for attachment to the label holder containing the label of a stock bin or the like, comprising a base member of sheet material having its ends slidably engageable with

5 said holder and adapted to be disposed in said holder beside said label and adjacent one end thereof, and a signal member secured to said base member and having a portion projecting from one side thereof, said signal member being adapted to be moved selectively in front of or behind said label in response to the sliding of said base member relatively to said label holder.

10 2. A stock condition indicator for attachment to the label holder containing the label of a stock bin or the like, comprising a base member of sheet material having its ends slidably engageable with said holder beside said label and adjacent one end thereof, a plurality of signal members secured to said base member and having a portion projecting from one side thereof, one of said projecting portions of said signal members being of greater length than the other projecting portion 15 and projecting therebeyond, said signal members being adapted to be moved selectively in front of or behind said label in response to the sliding of said base member relatively to said label holder.
